UNITED STATES PATENT OFFICE

106,341

DESIGN FOR A DRESS

Joan Bayor, New York, N. Y.

Application August 2, 1937, Serial No. 70,798

Term of patent 3½ years

To all whom it may concern:

Be it known that I, Joan Bayor, a citizen of the United States of America, residing in New York city, in the Borough of Manhattan, county and State of New York, have invented a new, original, and ornamental Design for a Dress, of which the following is a specification, reference being had to the accompanying drawing, forming part thereof, wherein,

The diagonal zipper closings on the waist and skirt portions have groups of fur tails at the ends thereof, as shown.

I claim:

The ornamental design for a dress, substantially as shown, and described.

JOAN BAYOR,
